UNITED STATES PATENT OFFICE.

STEPHEN J. HESTER, OF RAYMOND, MISSISSIPPI, ASSIGNOR OF ONE-HALF TO JAMES L. CARTER, OF MAYFIELD, KENTUCKY.

ADJUSTABLE FRAMING, DRAFTING, AND BEVEL SQUARE.

Application filed March 1, 1926. Serial No. 91,577.

The device forming the subject matter of this application is a square, adapted to be used for framing, drafting and beveling, the square comprising a body and an arm, and 5 novel means being provided for holding the arm at different angles with respect to the body.

Another object of the invention is so to construct the device that rafters and the 10 like may be cut by degree rather than by pitch.

It is within the province of the disclosure to improve generally and to enhance the 15 utility of devices of that type to which the invention appertains.

With the above and other objects in view which will appear as the description proceeds, the invention resides in the combination and arrangement of parts and in the 20 details of construction hereinafter described and claimed, it being understood that changes in the precise embodiment of the invention herein disclosed, may be made within the scope of what is claimed, without departing 25 from the spirit of the invention.

In the accompanying drawings:—

Figure 1 shows in plan, a square constructed in accordance with the invention, the square being opened for use;

30 Figure 2 is a detail enlarged from Figure 1;

Figure 3 is a section taken about on the line 3—3 of Figure 2;

35 Figure 4 is a fragmental plan showing the opposite side of the square from that which is delineated in Figure 1;

Figure 5 is an elevation wherein the square is viewed edgewise;

40 Figure 6 is a sectional plan showing a portion of the arm in relation to one of the side plates of the body of the square;

Figure 7 is a section taken about on the line 7—7 of Figure 6;

45 Figure 8 is a plan showing a portion of one of the side plates of the body of the square.

The square forming the subject matter of this application preferably is made of metal throughout, and includes a body 1 and an 50 arm 2 connected adjustably to one end of the body. The body 1 is made up of plates 3 and 4, a spacer 5 being secured between the plates 3 and 4, at the outer end of the body 1, so as to form a slot 6 in the body, into which 55 the arm 2 may be folded, when it is desired

to dispose the article in compact form. Adjacent to one end, the plate 3 has a beveled opening 7, in which is located a correspondingly beveled protractor disk 8, the disk 8 having a central beveled opening 9. By 60 means of one or more securing elements 10, the protractor disk 8 is connected permanently and rigidly to the arm 2, the construction being such that the arm 2 is mounted permanently on the plate 3 of the body 1 65 for swinging or pivotal movement with respect thereto. The plate 4 of the body 1 has an opening 11, and there is a tapered opening 14 in the arm 2, the opening 14 constituting a continuation of the beveled opening 9 in the protractor disk 8. The plates 70 3 and 4 and the arm 2 are united by a combined clamping and pivot member, including a bolt 12 located in the opening 11 of the plate 4, and having a flared head 15 which is received in the tapered opening 9 of the protractor disk 8 and in the tapered opening 14 of the arm 2. A wing nut 17 is threaded on the bolt 12 and is adapted to bear against the plate 4 of the body 1. The securing element 10 which unites the protractor disk 85 with the arm 2, projects a little way into the beveled opening 9 of the protractor disk 8, and the head 15 of the bolt 12 has a notch 16 which receives that portion of the rivet 10 that extends into the opening 9. The result 90 is that the securing element 10 holds the bolt 12 against rotation, so that the wing nut 17 may be tightened up readily.

The arm 2 is provided on one side, and 90 at its inner end, with seats 18, 19, 20, 21, 22 and 23, as Figure 6 will show. The side plate 4 has inwardly projecting pins 24 and 25. When the projection 24 is in the seat 21, and when the projection 25 is in the seat 19, the arm 2 will be disposed at right angles 95 to the body 1, at one side of the body. When the arm 2 is located at the opposite side of the body and at right angles to the body, the projection 24 is in the seat 18, and the projection 25 is in the seat 22. When the 100 arm 2 is housed within the body 1, between the plates 3 and 4, the projection 24 is received in the seat 23, and the projection 25 is received in the seat 20. The projections 105 of course may be held engaged with the proper seats by tightening up the wing nut 17, an observation which will be understood readily when Figure 3 of the drawings is 110 examined.

The plate 3 of the body 1 has an index 26, which cooperates with the protractor disk 8. The 90° marks on the protractor disk are located in a line that is parallel with the longitudinal axis of the arm 2, and the necessary settings may be obtained readily, with the arm 2 either at the right or at the left of the body 1.

As shown at 27, the body is inscribed with data which will enable a carpenter and joiner to make necessary rafter settings, with different bases, rise, degree to cut foot, degree to cut top, and the length of the piece being shown. In a similar manner, as shown at 28, the arm 2 may be inscribed for the convenience of the operator.

It will be understood that the wing nut 17 may be slackened away, and then the arm 2 may be placed at any desired angle with respect to the body 1, the index 26 cooperating with the protractor disk 8 to indicate the amount that the arm has been shifted from a position at right angles to the body 1. The arm 2 is held in the position to which it has been adjusted with respect to the body 1, by tightening up the wing nut 17.

What is claimed is:—

A square including an arm, and a body made up of side plates, the side plates being disposed on opposite sides of the arm, one side plate having an inwardly tapered opening, a protractor disk tapered to fit in the opening, the arm and the protractor disk

having registered tapered apertures, the other side plate and the arm being provided upon their inner contacting surfaces with positively interengaging socket and projection elements by which the body and the arm may be held at adjusted angles to each other when the arm is clamped between the side plates, a securing element connecting the arm with the protractor disk, whereby the tapered protractor disk will hold the first-specified side plate and the arm together, the securing element being extended laterally into the aperture in the protractor disk, a pivot and clamping member having a tapered head received in the aforesaid registering tapered openings and extended through the said other side plate, the periphery of the tapered head being provided with a notch receiving the part of the securing element that projects laterally into the aperture of the protractor disk, thereby to hold the pivot and clamping member against turning, and a nut engaging said other side plate, the nut being threaded on the pivot and clamping member and operating to clamp the side plates on the arm, and to hold the said interengaging elements interengaged.

In testimony that I claim the foregoing as my own, I have hereto affixed my signature.

STEPHEN J. HESTER.
